[57] CLAIM

The ornamental design for a toiletry kit, as shown and described.

DESCRIPTION

FIG. 1 is a perspective view of a toiletry kit embodying my new design;

FIG. 2 is a top plan view of the toiletry kit;

FIG. 3 is a rear elevational view of the toiletry kit; and
FIG. 4 is a bottom plan view of the toiletry kit.

The broken line showing of grooming articles in FIGS. 1-3 is for illustrative purposes only and forms no part of the claimed design.

FIG. 4
